UNITED STATES PATENT OFFICE.

WILLIAM N. ROBIRDS, JR., OF SANTA MONICA, CALIFORNIA.

FLOOR BUFFER.

Application filed March 24, 1921. Serial No. 455,024.

To all whom it may concern:

Be it known that I, WILLIAM N. ROBIRDS, Jr., a citizen of the United States, residing at Santa Monica, in the county of 5 Los Angeles and State of California, have invented new and useful Improvements in Floor Buffers, of which the following is a specification.

It is the object of this invention to provide a floor buffer or the like including a 10 rotatable buffer or brush, which is readily movable with relation to the frame of the device for adjusting the engagement between the buffer or brush and the surface 15 over which it moves.

More specifically it is the object of the invention to provide a movable frame carried upon wheels, and supporting the adjustable buffer or brush, and also supporting means, 20 such as an electric motor, for rotating the buffer, the driving connection between the motor and brush being so arranged as to provide for vertical adjustment of the buffer while maintaining said driving connection. 25

The invention will be readily understood from the following description of the accompanying drawings, in which:

Figure 1 is a front elevation of a device 30 constructed in accordance with the invention.

Fig. 2 is a side elevation of the same.

Fig. 3 is a transverse section on the line 3-3 of Fig. 2.

Fig. 4 is a side elevation showing the driving connection between the buffer and its motor with the side of the casing for the device removed.

Fig. 5 is a detail section on the line 5-5 40 of Fig. 1.

Fig. 6 is a detail perspective view of the buffer and the mandrel upon which it is mounted.

Figure 7 is an enlarged fragmentary sectional view of one of the adjustable supporting means for the shaft and brush.

The improved buffer consists of a casing 1 having side plates 2 and 3. Wheels 4 are provided upon stub shafts 5 projecting from 50 side plates 2 and 3 at the lower edge of the front of the buffer casing. One of the side plates, shown as side plate 2, is continued rearwardly and upwardly as shown at 2^a, so as to form a cover for a casing 6 projecting rearwardly and upwardly from one side 55

of casing 1, and this extension 2^a terminates in a depending arm 7 supporting a wheel 4^a upon a stub shaft 5^a at the lower edge of the rear of the device. The side plate 3 is provided with a rearward extension 3^a, 60 which supports a similar wheel 4^a upon a stub shaft 5^a.

A suitable electric motor 8 is mounted in rear of casing 1 and is supported thereby, and the shaft of this motor extends within 65 casing 6, and is provided with a pulley 9, over which is received a belt 10 for actuating the buffer or brush of the machine.

The buffer carried by the machine, includes a shaft 12 having a mandrel 13 70 mounted thereon, and provided with the buffering element. In the present instance this element is shown as detachable from the mandrel so that various elements may be employed, and the specific element illustrated includes a flexible backing 14 received around the mandrel and secured by fastenings 14^a with bristles 15^a projecting from said backing. It will be understood that any other suitable element such as a 80 cloth covered buffering element or a sheet of sand paper may be used.

End plates 15 are fixed to mandrel 13, and one of the same is formed as a pulley 16, over which belt 10 is received, so that the 85 electric motor 8 will rotate the buffering element. The ends of shaft 12 are received through suitable slots 18 provided in said plates 2 and 3 so that the buffering element may be moved in said slots for adjusting the contact between the same and the surface over which the device is moved, or may be removed entirely from the machine. The slots 18 are so curved as to maintain driving belt 10 taut, irrespective of the position in said 90 slots to which the buffering element is adjusted.

The means for retaining the ends of shaft 12 in adjusted positions within slots 18, preferably, includes bearings 20 received 100 upon said shaft ends, and provided with flanges 21 engaging the inner surfaces of the walls of slots 18. The outer ends of these bearings are threaded as shown at 22, so as to receive end caps 23, which when 105 tightened upon the bearings will clamp the same in adjusted positions within the slots.

A graduated scale 18^a is preferably provided along the sides of slots 18, and the end caps are formed with indicator mem- 110

bers adapted to be alined with the scale markings for moving the buffer element to a predetermined position.

A suitable handle is, preferably, provided for the device, including a yoke 25 having its ends pivoted to the casing of the machine as shown at 26, and also having a handle 27 extending rearwardly from said yoke. Suitable projecting means shown as a strip 10 28 of yieldable material, such as rubber, is preferably provided around the lower edge of the casing of the machine in order to not mar furniture or the like against which the buffer may be moved.

15 It will thus be seen that I have provided an extremely simple buffer construction, wherein the buffer or brush is rotated by a suitable motor mounted upon the device, and wherein the buffer is readily adjustable up and down, so as to vary its contact with a surface to be polished.

Various changes may be made without departing from the spirit of the invention as claimed.

25 What is claimed is:

1. A device of the character described comprising a casing, side plates secured to the casing and formed with inclined slots, a buffer sustaining shaft having its ends

extending into the slots, cup-shaped bearing members receiving the ends of said shaft, and slidable in said slots, flanges formed on the inner ends of the members for engagement with the inner sides of the side plates, and end caps threadedly engaging said members and disposed at the outer sides of said plates to cooperate with said flanges in locking the members in any adjusted position within said slots.

2. A device of the character described comprising a casing having slots therein, a movable member, a driving member for the movable member, a rotatable member carried by the movable member for engaging a surface, a belt connection between said driving member and rotatable member, and means for adjusting the rotatable member relative to said surface while maintaining said belt taut comprising bearing members adapted to receive the ends of the rotatable member and extending into said slots, and caps releasably engaging the bearing members and cooperating with the latter and said casing for clamping the rotatable member in any adjusted position.

In testimony whereof I have signed my name to this specification.

WM. N. ROBIRDS, JR.
